UNITED STATES PATENT OFFICE

WILLIAM O. JOURNEY, OF HOUSTON, TEXAS; JAMES JOURNEY ADMINISTRATOR OF
SAID WILLIAM O. JOURNEY, DECEASED

DRILL BIT

Application filed September 16, 1925. Serial No. 56,619.

This invention relates to new and useful improvements in drill bits, and more particularly to that class of drill bits adapted for use in deep well drilling.

5 One object of this invention is to provide a drill bit which will drill a straight hole and ream the sides of the hole as the drilling progresses.

10 Another object of the invention is to provide the head of the bit with removable blades.

Another object of the invention is to provide means for cutting a way backward in case a boulder should fall in on top of the 15 bit, or in case of the wall caving in, or "bridging".

With the above and other objects in view this invention has particular relation to certain novel features of construction, operation 20 and arrangement of parts, an example of which is illustrated in the accompanying drawings and described and claimed in this specification, wherein:—

25 Figure 1 shows a vertical sectional view of the bit, taken on the line 1—1 of Figure 3.

Figure 2 is a cross sectional view taken on the line 2—2 of Figure 1.

Figure 3 is a cross sectional view of the bit taken on the line 3—3 of Figure 1.

30 Figure 4 shows a bottom end view of the bit, partly in section.

Figure 5 is a fragmentary longitudinal sectional view of the bit illustrating the method of holding the bit blades in the bit head.

35 Figure 6 is a view of the type of bolt used in holding the blades in the bit, while

Figure 7 is an end view of the head of the bolt showing the recess in which a suitable wrench may be applied when screwing or unscrewing the bolt.

40 Referring now more particularly to the drawings wherein like numerals of reference designate similar parts in each of the figures the numeral 1 refers to the bit head as a whole, 45 which in general contour is cylindrical, hav-

ing, however, the longitudinally extending grooves 2, and also the longitudinal grooves 3 in which the elongated blades 4 are seated. These grooves are slightly tapered inwardly toward the axis of the head and the blades are held against removal by the bolts 5, all of which pass through the shoulders 6 and 7 which form the grooves 2, except the top bolts.

The blades 4 extend practically the entire 55 length of the bit head and project outwardly and beyond the lower end thereof as shown in Figures 1 and 5, the extended portions being inclined forwardly to the cutting edge. The projecting lower ends also project inwardly practically to the center of the head some further than others so that the bottom 60 of the hole will be cut out. The bottom edges of the blades taper slightly upwardly, thus causing the bit to center better than if these 65 edges were straight across. The shoulders of the blades are seated in grooves in the bottom of the head and are thus braced against twisting off.

Secured in the grooves in the top 9 of the 70 head are the blades or cutters 10, substantially triangular in shape, the upper edges of which are forwardly inclined and sharpened so that if a boulder should fall on top of the bit in course of drilling, or if the hole should cave in above the drill the drill pipe may be raised, held under constant tension, and rotated and the boulder ground to pieces or the caved in portion cut through in this manner. A suitable collar 11 is screwed down upon the bit 75 head and is held by the lugs carried by the blades 10 in rigid position on the head 1. The blades in turn are held rigid by the shoulders of the head and bolts 12.

The particular type of bolts used in holding the blades in position are found to be of 80 value since they may be removed easily by the use of a special wrench being inserted in the socket 13 in the head of said bolt and if desired a screwdriver may be used in the small 85 90

or advance end thereof to assist in removing the bolt should the same become too tight to be removed easily by the use of the wrench alone. Suitable water courses 14 have been provided for flushing the cuttings and washing the bit points.

The blades may be easily removed to be sharpened or for the purpose of inserting new ones where needed.

10 This type of bit is easily made and assembled or disassembled and is cheaply constructed.

What I claim is:—

1. A drill bit comprising a head having external grooves extending longitudinally thereof from end to end thereof and whose lower ends extend radially across the bottom of the head, cutting blades seated in said grooves and projecting beyond the lower end 20 of said head and shoulders carried by said blades which project under the head some further than others, said shoulders being seated in the radial end grooves, means for bracing said projecting portions of said 25 blades and bolts spaced along said blades and securing said blades in said grooves.

2. A drill bit comprising a head having grooves extending longitudinally from end to end thereof in the outer side of said head, 30 cutting blades seated in said grooves and co-extensive therewith and projecting beyond the lower end of said head and a shoulder carried by each blade which projects under the head, some of said shoulders projecting 35 further than others, and which seat in said grooves, said shoulders projecting toward the center axis of the head and bolts securing said blades in said grooves, other blades upon the upper end of said head seated in grooves in 40 the head and having their upper edges sharpened.

3. A drill bit comprising a head having external grooves spaced apart therearound and extending from end to end thereof blades 45 seated in said grooves and extending from the upper end of the head to the lower end thereof said blades extending beneath the lower end of the head, the upper and lower ends of the head having radial grooves aligned with said 50 longitudinal grooves, said extensions extending inwardly and being seated in said lower end grooves, blades seated in said upper end grooves having upper cutting edges which diverge downwardly.

55 4. A drill bit comprising a head having external longitudinal grooves extending from end to end thereof, the upper and lower ends of the head having radial grooves aligned with the corresponding longitudinal grooves, 60 blades seated in said longitudinal grooves which extend beneath the head, and are widened inwardly and seated in said radial grooves at the lower end of the head, blades seated in said radial grooves at the upper 65 end of the head whose upper edges are formed

into sharp cutting edges, the upper end of the head being reduced to form an external annular shoulder said blades at the upper end of the head extending inwardly and a collar screwed onto the reduced portion of the head and clamping said inwardly extending portions of said blades between said collar and shoulder.

In testimony whereof I have signed my name to this specification.

70 WILLIAM O. JOURNEAY.
